UNITED STATES PATENT OFFICE.

JOSEPH F. DONAHUE, OF SOUTH BEND, INDIANA.

SHINGLE ROOFING.

Application filed August 11, 1923. Serial No. 656,923.

To all whom it may concern:

Be it known that I, JOSEPH F. DONAHUE, a citizen of the United States, residing at South Bend, in the county of St. Joseph and State of Indiana, have invented certain new and useful Improvements in Shingle Roofing, of which the following is a specification.

The invention relates to shingle roofing, and has for its object to provide a roof formed from a plurality of interlocked shingles wherein the roof after being covered by the shingles, has substantially a double covering of shingles, and at the same time to accomplish this result with a minimum number of shingles.

A further object is to provide a roof formed from a plurality of interlocked shingles laid in horizontal courses, said courses overlapping adjacent courses, and interengage in a manner whereby curling of the shingles will be prevented, and the courses locked together.

A further object is to provide a shingle roof formed from a plurality of shingles, preferably of the pliable type, which shingles comprise rectangular shaped body portions having their ends in abutting engagement thereby forming courses of shingles, and V-shaped projections carried by the sides of the body portions and having their converging sides provided with slots for receiving the adjacent converging sides of shingles in the adjacent course. The shingles are preferably of greater length than width, therefore a minimum amount of overlapping of shingles of adjacent courses is obtained, and the area of the roof covered by three plies of shingles or portions of shingles is reduced to a minimum, thereby allowing the covering of a roof with two plies of shingles with a minimum number of shingles.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a top plan view of a section of roofing showing the interengaged shingles.

Figure 2 is a plan view of one of the shingles.

Figure 3 is a perspective view of adjacent shingles showing the same interengaged.

Referring to the drawing, the numeral 1 designates a portion of a roof formed from a plurality of shingles 2. The shingles 2 comprise rectangular shaped body portions 3, which are preferably oblong shaped, and V-shaped extensions 4 extending from one of the sides thereof, and having their converging sides 5 spaced from the ends 6 of the body portion, thereby forming shoulders 7. The shingles are preferably of greater length than width, thereby allowing a minimum amount of overlapping for securing a roofing comprising two plies of shingles. The outer ends of the extensions 4 are preferably cut off as at 8, thereby obviating points when the roof is formed, which points have a tendency to curl incident to weather and heat, and at the same time are proportioned in relation to the body 3 of the shingles for preventing overlapping, as will be herein-after set forth. The shingles 2 are laid in courses horizontally as shown in Figure 1 with their rectangular shaped portions 3 in abutting engagement, and with their extensions 4 extending in the same direction, and in vertical relation to the roof. The shingles of each course may be nailed in position if so desired during the laying of the roof. The roof is preferably laid in courses from the top downwardly. After the upper course has been laid, the next course is placed in position beneath the upper course, by placing the body portions 3 of the next course beneath the projections 4 of the course above, thereby underlapping or underlying the body portions of the shingles of the course above, at which time the opposite converging edges 5 of the shingles of the course being laid are placed in inwardly extending slits 9 of the projections 4 of the course previously laid, thereby interlocking the shingles of each course with the shingles of adjacent courses at points between the projections 4. The shoulders 7 prevent downward movement of the shingles and consequently each course is interlocked and held against displacement in relation to each other. It will be noted that the projections 4 of adjacent courses are in staggered relation, thereby providing a symmetrical outline and an artistic appearance for the roof. The shingles are proportioned whereby a minimum amount of overlapping is provided, and at the same time propor-

100
105
110

tioned whereby when the shingles are positioned on a roof a double ply of shingles will cover the entire roof, which is sufficient for all practical purposes, thereby reducing the 5 number of shingles necessary for covering a roof, to a minimum, and reducing the three ply points to a minimum for instance the only three ply points are formed by the V-shaped portions 10 adjacent the slots 9, 10 which portions are relatively small in area. The cutaway ends 8 of the projections 4, when the roof is formed register with the outer sides 11 of the rectangular shaped portions 3 of shingles below the shingles, the 15 particular portion 4 overlies, thereby obviating three ply roofing at the lower ends of the projections 4. Although the forming of the roof has been described as starting at the top of a roof and working downwardly, it is 20 obvious that this operation may be reversed, and the roof laid from the bottom or eaves upwardly to the ridge of the roof.

From the above it will be seen that a roof is provided which is formed from a plurality of substantially T-shaped shingles, laid 25 in horizontal courses and the shingles of adjacent courses in staggered relation and interlocked, and that the shingles are propor-

tioned in a manner whereby a two ply roofing is formed with a minimum amount of 30 three ply overlapping points.

The invention having been set forth what is claimed as new and useful is:—

A roof formed from a plurality of independent horizontally and vertically alined shingles, said shingles comprising rectangularly shaped body portions having their adjacent ends in abutting engagement in each course horizontally, angularly disposed projections carried by the lower side of each of the body portions, said projections being spaced from opposite sides of the body portions, thereby forming shoulders in horizontal alinement with each other, said projections having their sides converging towards their ends and provided with slits intermediate their ends, said projections interengaging with adjacent diverging sides of adjacent angularly disposed projections, the shoulders formed by the angularly disposed projections forming means cooperating with the slits for preventing movement of the shingles and maintaining the same in horizontal courses. 45

In testimony whereof I affix my signature.

JOSEPH F. DONAHUE. 50
